UNITED STATES PATENT OFFICE.

OSCAR B. BACH, OF NEW YORK, N. Y.

DESIGN FOR A FIREPLACE SCREEN.

Application filed March 9, 1928. Serial No. 25,787. Term of patent 3½ years.

To all whom it may concern:

Be it known that I, OSCAR B. BACH, a citizen of the United States, residing at New York city, in the county of New York and State of New York, have invented a new, original, and ornamental Design for a Fireplace Screen, of which the following is a specification, reference being had to the accompanying drawing, forming a part hereof, of which the figure is a front view slightly in perspective of the article showing my new design.

I claim:

The ornamental design for a fireplace screen, as shown.

OSCAR B. BACH.
